UNITED STATES PATENT OFFICE.

LEVI LUND, OF GRAND FORKS, NORTH DAKOTA, ASSIGNOR OF ONE-HALF TO EMIL PETERSON, OF EAST GRAND FORKS, MINNESOTA.

CONCRETE MIXER.

Application filed February 25, 1922. Serial No. 539,243.

To all whom it may concern:

Be it known that I, LEVI LUND, a citizen of the United States, residing at Grand Forks, in the county of Grand Forks and 5 State of North Dakota, have invented certain new and useful Improvements in Concrete Mixers; and I do hereby declare the following to be a full, clear, and exact description of the invention, such as will 10 enable others skilled in the art to which it appertains to make and use the same.

This invention relates to a mixing device, particularly designed for mixing concrete. The device is of the type having a revoluble 15 vessel in which the materials to be mixed are charged, and which vessel is arranged to be tilted to discharge the material. The device is also mounted on a truck frame so as to be especially convenient for use in road work, 20 and to be readily transportable.

It is an object of the invention to provide such a mixer with simple and efficient means for rotating and tilting the same. It is a further object to mount the mixing container 25 on a frame, together with a motor and to provide simple and efficient transmission mechanism for rotating the vessel and for controlling and operating the tilting mechanism.

These and other objects of the invention 30 will fully appear from the following description made in connection with the accompanying drawings in which like reference characters refer to the same parts 35 throughout the different views, and in which,

Fig. 1 is a view partly in side elevation and partly in longitudinal section of the device showing different positions thereof;

Fig. 2 is a plan view of the device;

Fig. 3 is a partial horizontal sectional view on an enlarged scale; and

Fig. 4 is a partial view in side elevation of a part of the device.

Referring to the drawings, the device comprises a frame member 1 having longitudinal side members and supporting end members, which frame is mounted upon suitable truck wheels at the front and rear thereof. The side members of the frame are preferably 45 in the form of angle bars and to the front ends of the horizontal portions thereof are secured a pair of brackets 2 shown as of plate material having their ends upturned to form bearings for transversely extending

cylindrical rods 3. These rods are flattened 55 at their inner ends and bolted or otherwise suitably secured to the front end of a flat ring member 4. A U-shaped member 5 formed of a flat metal strip has its ends outwardly turned and bolted to the inside of the ring 60 4 and extends rearwardly longitudinally of the frame. The ring member 4 has a second plate 6 bolted thereto and spaced therefrom at its lower portion which is semi-circular 65 in shape. Rollers 7 are rotatably mounted 70 on members extending between and secured to the plates 4 and 6 and these rollers form the forward support for a substantially cylindrical vessel or barrel 8, which has projecting from its rear end a short axle shaft 75 9 journaled in an aperture formed in the rear part of the member 5, which shaft has suitable collars secured thereto at each side of the member 5 to hold the same in correct 80 position. A plate member 10 is bolted to the rear portion of the member 5 and extends downwardly therefrom and is connected to a curved flat bar 11 which extends forwardly under the barrel 8 and is connected at its front end to the members 6 and 7.

A crank shaft 12 is journaled at its ends in bearings secured to the side members of the frame 1 and this shaft has a roller 13 journaled on its crank portion upon which the plate 11 rests. This crank shaft is provided at one side of the frame with a large gear 14 driven by a pinion 15 secured to a short shaft supported on the side member, to which shaft is also secured a comparatively larger gear 16 which is, in turn, 85 arranged to mesh with and be driven by a pinion 17. The latter pinion is mounted on a shaft 18 extending between the side members of the frame and supported in bearings thereon and this shaft is arranged to be 90 driven by a sprocket wheel 19 over which runs a chain 20 driven by a sprocket 21, which sprocket is secured to the crank shaft 22 of a suitable motor 22^a mounted on the frame 1 diagrammatically illustrated as of 100 the internal combustion engine type. The pinion 17 is loosely mounted on the shaft 18 and is formed to constitute one member of a clutch, the other member 23 of which is splined on the shaft 18 and is normally 105 held out of engagement with the pinion 17 by a coiled compression spring 24 housed therein. A clutch lever 25 is pivoted at one

end to the rear of shaft 18 and has a collar formed thereon encircling said shaft and disposed between a collar 26 pinned to the shaft 18 and the member 23. When this 5 lever is swung about its pivot toward the adjacent side member of the frame, the member 23 is moved into engagement with the pinion 17 so that the latter will be driven by the shaft 18. The lever 25 extends forward 10 from the shaft 18 and has one end thereof somewhat flattened and arranged to bear against the side of a cam disk 27 secured to the crank shaft 12. This cam disk has a sector shaped portion thereof 15 separated by a slit from the main body of the cam and bent laterally, as shown in Figs. 2 and 4. A flexible member or cable 35 is shown as secured to the lever 25 adjacent the shaft 18. This cable passes laterally 20 over a pulley 36 secured to one of the side members of the frame and this cable then passes forwardly along said side member and over another pulley mounted at the end of the frame. This cable is adapted to be 25 used as manipulating means for the lever 25.

In order to rotate the container 8 the sprocket 19 is formed to constitute one member of a clutch and the other sprocket 28 is splined on the shaft 10 to slide thereon and 30 to be moved into engagement with the sprocket 19 and clutch the same so as to be driven thereby, the sprocket 28 being moved, as desired, by a clutch lever 29 provided with the usual clutch fork engaging in a groove 35 therein. A shaft 30 is journaled at one end of the frame in bearings secured to one of the side members and the member 5 and carries a sprocket over which is adapted to run a chain 31 driven by a sprocket 28. The 40 shaft 30 has a beveled gear at one end meshing with another beveled gear secured to a shaft 32 mounted in bearings bolted to one side of the member 5. This shaft 32 has secured to its rear end a spur pinion 33 which 45 meshes with a larger annular gear 34 secured to and surrounding the rear end of the member 8. It will be noted that the member 8 is provided with a part 8^a forming a convenient discharge portion. The member 8 is 50 also provided on its interior with suitable mixing blades not shown.

With the above structure, when the motor 23 is operated the shaft 18 will be driven and when it is desired to rotate the member 8, 55 after the material has been charged therein, the clutch lever 29 will be thrown to connect sprockets 19 and 28. The member 8 will then be rotated through the shafts 30 and 32 by pinion 33 turning the gear 34. At 60 this time, the barrel or container 8 will occupy substantially the position shown in Fig. 1. When the material has been sufficiently mixed and it is desired to discharge the same, the operator, who will usually be 65 at the front of the machine, will pull upon

the cable 35 and this will, in turn, swing the lever 25 toward its adjacent side member and will cause the engagement of the clutch member 24 with pinion 17. The outer end of the lever 25 at this time has moved toward the center of the frame and rests against the bent-out sector of the disk 27 (see Fig. 4). When the lever is moved, to engage the clutch members, as stated, the end of the lever will be brought to one side of the cam 75 27, as shown in Fig. 2. When the members 23 and 17 are engaged, the cam 27 immediately begins to revolve and the flat portion of the cam soon passes across the end of the lever and this end of the lever then bears 80 against the flat portion of the cam and the clutch is held in engagement for substantially one revolution of the crank shaft 12. As the crank shaft revolves, the roller 13 is moved from the position shown in full lines in Fig. 1 to the position shown in dotted lines and the barrel 8 is, likewise, moved into the position shown in dotted lines in said figure. The material will thus be discharged as 85 the container is in this position. A continued rotation of the crank shaft again allows members 13 and 11 and the container 90 8 to resume their normal position. When this position is again attained, the end of the lever 25 has reached the bent-out sector 95 on the cam 27 and will again move toward the center of the frame in contact with the edge of said sector. This will allow the members 23 and 17 to disengage and the container 8 will be rotated without the crank shaft 12 revolving until the cable 35 is again pulled to engage the members 23 and 17.

The shaft 18 is shown with a squared end to receive a handle crank, so that the shaft 105 can be turned by hand and the member 8 discharged when the engine is not running.

From the above description it is seen that applicant has provided a simple and efficient construction of concrete mixer. The transmission parts are few and simple and the rotation and tilting movement of the mixing vessel are easily controlled. It will be noted that the rotating transmission mechanism is located adjacent one side member of the frame and the tilting transmission mechanism is located adjacent the other side member. The shafts for supporting the mechanisms are thus easily mounted on the side frame members. The machine can be constructed of material which is easily obtainable in standard shapes and the structure is quite rugged and has no tendency to become disarranged. With the device, the concrete can be quickly and efficiently mixed 110 and can be discharged readily when desired at the required location.

It will, of course, be understood that various changes may be made in the form, detail and arrangement of the parts without 115 120 125 130

departing from the scope of applicant's invention, which, generally stated, consists in the matter shown and described and set forth in the appended claims.

5. What is claimed is:

1. A concrete mixer having in combination, a frame, a rotatable vessel mounted therein, said frame and vessel being arranged for tilting movement about a transverse axis, a member extending longitudinally from one end thereof, rotating a crank member adapted to engage said member to tilt the vessel, and transmission means having a common actuator for rotating said vessel and crank member.

2. A concrete mixer having in combination, a frame, a substantially cylindrical vessel mounted for rotation about a longitudinal axis and for tilting movement therewith about a transverse axis at one end thereof, said vessel being closed at one end and having a charging and discharging opening at the other end, means for rotating said vessel, a curved plate connected with said frame extending beneath and rearwardly from said vessel, and a crank shaft on said frame adapted to co-operate with said plate, to tilt the mixer.

3. A concrete mixer having in combination, a frame, a vessel mounted at one end thereof, for rotation relative thereto about a longitudinal axis and tilting movement therewith about a transverse axis, a member extending rearwardly from said vessel and secured the said frame, a crank shaft journaled in said frame and adapted to co-act with said member to tilt the vessel, a power shaft on said frame, driving means for said crank shaft, a clutch for connecting said driving means to said power shaft, a lever for operating said clutch, and means on said crank shaft for holding said lever in position to hold said clutch engaged for substantially one revolution of said crank shaft whereby the vessel is tilted upwardly and downwardly.

4. The combination set forth in claim 3,

said last named means comprising a revolvable disk cam.

5. The structure set forth in claim 4, said cam having a sector thereof bent laterally and spaced at one radial edge from the body of said cam.

6. The structure set forth in claim 3 and a flexible means secured to said lever and extending to the front of the frame and forming a manipulating means for said lever.

7. A concrete mixer having in combination, a stationary frame comprising spaced side members, a tilting frame, a substantially cylindrical container mounted on one end of said latter frame for rotation about a longitudinal axis and for tilting movement therewith about an axis extending transversely at the end of the frame, a power means on said frame, a crank shaft on said frame carrying a cam roller for tilting said container, transmission means secured to said tilting frame with which said roller engages, mechanism for rotating said container adapted to be connected to said power means, and located adjacent one of the side members of said stationary frame, and transmission mechanism adapted to rotate said crank shaft disposed adjacent the other side member of said stationary frame.

8. A concrete mixer having in combination, a stationary frame, a tilting means therefor carrying a revolvable container, means for tilting said means comprising a rotating crank shaft, means for revolving said container including a clutch, and means for holding said clutch engaged for substantially one revolution of said crank shaft and then permitting said clutch to be released.

9. The structure set forth in claim 8, said last named means comprising a lever for operating said clutch, and a slotted cam disk on said crank shaft co-operating with said lever.

In testimony whereof I affix my signature.

LEVI LUND.
